UNITED STATES PATENT OFFICE.

SAMUEL CHENEY, OF WICKEPIN, WESTERN AUSTRALIA, AUSTRALIA.

AUTOMATIC ADJUSTING AIR-ESCAPE VALVE FOR RAILWAY-BRAKES.

1,137,576.

Specification of Letters Patent. Patented Apr. 27, 1915.

Application filed November 23, 1914. Serial No. 873,577.

To all whom it may concern:

Be it known that I, SAMUEL CHENEY, a subject of the King of Great Britain, and residing at Wickepin, Western Australia, 5 Commonwealth of Australia, have invented certain new and useful Improvements in Automatic Adjusting Air-Escape Valves for Railway-Brakes, of which the following is a specification.

This invention has been devised to provide an automatically working appliance to be used in open communication with that portion of the pneumatic brake system known as the "train pipe" the object of the invention being that in case of emergency a sudden freeing of the air pressure may be accomplished so that the brakes may be quickly applied.

In order that my invention may be clearly understood the same will be explained with the aid of the attached drawing wherein the figure represents the invention in sectional elevation.

In apparatus embodying my invention which may be modified to suit varying working conditions of the train brake gear I employ a depending open cylinder as *a* the neck *b* of which interscrews with a *T* piece of the train air pipe. The lower part of this cylinder *a* is internally screw threaded as at *c* so as to interscrew with the bottom of a sleeve cylinder *d* thus forming two cylinders as *a* and *d* the cylinder *d* being open mouthed at its top end thus communicating with the upper and larger cylinder as *a* and providing a resultant and annular space as *e* between said cylinders.

In the interior cylinder *d* are a number of air inlet holes *f* placed radially and giving free access with the said annular space *e* as shown. The cylinder *d* suitably connects by screw thread with the cylinder *g* which latter is of a lesser internal bore than that of the cylinder *d* thus resulting in differential areas for the respective pistons *d*¹ and *g*¹.

The cylinder *g* is formed with radially arranged air exit holes *j* opening to the atmosphere, said cylinder *g* at its bottom having a threaded neck *k* whereby connection is made with the air reservoir *k*¹. In the smaller cylinder *g* is a piston *g*¹ carried on the bottom end of the tubular piston rod *g*² and said rod at its upper end carries the piston *d*¹ working in its cylinder *d*. The bore of the tubular piston rod *g*² at its upper end is restricted to a suitable degree by a

small removable screw cap *d*² having a contracted orifice for the admission of air into the reservoir *k*¹.

This invention makes provision whereby upon a sufficient release of air pressure in the train pipe the compound tandem pistons *d*¹ and *g*¹ will move upward thus causing piston *d*¹ to uncover the air inlet ports *f* as shown by broken lines and so allowing air to escape therethrough and underneath piston *d*¹ and thence into the cylinder *g* and so by way of the exit ports *j* into the outer atmosphere. The object of the contracted neck *d*² in the top of the tubular piston rod 70 is to provide a retardation of the air exhaust from the reservoir *k*¹ when a rapid reduction of air pressure takes place in the train pipe. This retardation of air exhaust allows a superior pressure to be exerted on 75 the bottom face of the piston *g*¹ and consequently causes the upward movement of both pistons and as soon as the air in the train pipe and reservoir has been fully exhausted the pistons will fall by gravity to 80 the position as seen in full lines in the drawing. When the train pipe is again charged the air will flow into the reservoir *k*¹ through the contracted neck *d*² and tubular piston rod. The orifice in said neck *d*² is of an 85 approved area to exhaust the air from the reservoir within a given time limit and to suit the proper working requirements of the train brake gear as a whole. I may employ a spiral spring and interpose it between 90 the piston *d*¹ and the underside of the neck *b* of cylinder *a* so that its expansive function may operate to press down said piston and assist in its fall by gravity when the air has fully escaped from reservoir *k*¹ 95 while on the upward stroke of the piston the spring prevents it from leaving its cylinder *d*.

What I claim as my invention and desire to secure by Letters Patent is:—

1. In air brake apparatus, an automatically acting air escape valve comprising a casing having a pair of cylinders of different diameters, the larger cylinder adapted to be connected to the train pipe and the smaller cylinder to an air reservoir, pistons working in said cylinders, and a tubular rod connecting the pistons and providing means for conducting air between the operative faces of the pistons, air vents being formed 110 in the casing between said pistons, and the larger cylinder having ports in its wall ar-

ranged to be uncovered by the respective piston to admit the flow of train pipe air to said vents.

2. In air brake apparatus, an automatically acting air escape valve comprising a pair of cylinders of different diameters, the larger cylinder adapted to be connected to the train pipe and having ports in the wall thereof to admit air from the train pipe to such cylinder, and the smaller cylinder adapted to be connected to an air reservoir and having air vent ports in its wall, pistons working in said cylinders, the piston in the larger cylinder opening and closing the ports therein in its movements, and a tubular rod connecting said pistons in tandem and serving to feed air between the train pipe and said reservoir.

3. In air brake apparatus, the combination of a pair of cylinders of different diam-

eters, the cylinder of larger diameter having one end in communication with the train pipe and also having ports in its side wall to admit air thereto from the train pipe, and the smaller cylinder having one end in communication with an air reservoir and having air vent ports in its side wall, pistons working in said cylinders, the piston in the larger cylinder controlling said air administration ports therein, and means connecting said pistons in tandem and providing air communication between the operative faces of the pistons.

In testimony whereof I have hereunto set my hand in presence of two subscribing witnesses.

SAMUEL CHENEY.
